(Cl. D57—1)

The dominant features of my design reside in the portions shown in solid lines.

This is a division of my copending application Ser. No. D. 86,952, filed Sept. 13, 1965.

I claim:

The ornamental design for a pair of clip-on sunglasses, substantially as shown and described.
